UNITED STATES PATENT OFFICE.

HUBERT KEMPF AND AUGUST HARTMANN, OF BARMEN, GERMANY, ASSIGNEES TO THE FIRM "CUPRUM" AKTIENGESELLSCHAFT, OF CLARUS, SWITZERLAND.

APPARATUS FOR SPINNING ARTIFICIAL SILK.

Application filed April 1, 1924. Serial No. 703,490.

To all whom it may concern:

Be it known that we, HUBERT KEMPF, a citizen of the Republic of Germany, residing at Barmen, Germany, and AUGUST 5 HARTMANN, a citizen of the Republic of Germany, residing at Barmen, Germany, have invented certain new and useful Improvements in Apparatus for Spinning Artificial Silk; and we do hereby declare the following to be a clear, full, and exact description of the invention, such as will enable others skilled in the art to which it appertains to make and use the same, reference being had to the accompanying drawings, and to letters or figures of reference marked thereon, which form a part of this specification.

The present invention relates to improvements in apparatus for spinning artificial 20 silk.

Apparatus for spinning artificial silk according to the tension method are known in which the precipitation liquid is fed into a cylinder in the top part of the latter and 25 approximately in the same elevation as the nozzle, whereupon this liquid flows slowly down inside the cylinder together with the not yet solidified threads, in order to pass thereupon together with the threads into a 30 conical funnel in which the speed of the flow increases as the area decreases. Used precipitation liquid has been fed into this apparatus from below in order to pass through the apparatus in unison with the 35 fresh precipitation liquid. The used precipitation liquid enters laterally above the edge of the funnel into the stream of the fresh precipitation liquid.

This known installation presented the advantage that at the beginning the flow of 40 the precipitation liquid is comparatively slow and its speed increases progressively only from the moment in which it enters the inserted conical funnel.

45 A disadvantage of the known installation consists in the fact that the entrance of the precipitation liquid fed from below does not always occur uniformly but often in a one-sided manner so that the bundles of 50 threads issuing from the nozzles are frequently displaced to one side, whereby faults in the spinning process occur.

These disadvantages are overcome by the 55 present invention without impairing the advantages of the known installation by intro-

ducing the whole precipitating liquid below the upper edge of the conical funnel inserted in the cylinder.

A constructional example of the subject matter of the present invention is illustrated on the accompanying drawing, in which:

Fig. 1 is a vertical section through the apparatus and

Fig. 2 shows in an elevation an apparatus applied to a spinning installation.

The precipitating liquid supplied from below by the pipe *d* (Fig. 1) enters an annular chamber *c*, and hits against the inner wall of the latter. It is distributed uniformly and passes thereupon through the annular spaces *f* and *g* into a cylinder *b* from which it flows uniformly along the whole circumference over the upper lip and opening of a conical funnel *e* and is then discharged through the discharge tube *t* provided at the lower end of the funnel. A supply of fresh precipitating liquid from above into the cylinder *b* is not necessary, as the flow of the precipitating liquid 75 through the annular space *g* in the upward direction will cause a small portion of the liquid to rise in the cylinder *b* along the wall of the latter and to displace by degrees a portion of the precipitating liquid 80 contained therein, which liquid has already absorbed some of the solvent from the threads passing therethrough. This displacement of the precipitating liquid inside the cylinder *b* of the spinning apparatus 85 and the thereby resulting renewal respectively is necessary as it absorbs the solvent for the cellulose from the threads and as the precipitation or the solidifying of the threads would be prevented if the precipitating liquid were too much saturated with the solvent. The movement of the precipitating liquid in the cylinder *b* is, however, exceedingly small as compared with the movement through the conical funnel *e* and 95 this is necessary as otherwise the pulling out of the threads would occur too quickly so that the threads have not sufficient time to solidify. The threads would be broken as they do not possess sufficient strength in 100 this case.

The spinning process is carried out in the following manner:

Solution of cellulose is contained in the tank *k* (Fig. 2) and the solution is sup- 110

plied to the spinning apparatus by means of the pipe *r*. At the end of the latter a spinning head *p* is provided having a large number of apertures from which the single threads issue. The threads move at first through the cylindrical space *b* of the apparatus in which the precipitating liquid moves only slowly (i. e. is almost at rest), the threads are somewhat drawn out within the space *b* and solidify to some extent. Then they get into the conical funnel *e* made of glass in which the precipitating liquid, which flows at a higher rate, acts upon the threads and completes the drawing out of the threads which thereby completely solidify. After the threads have left the discharge tube *t* they are wound upon a known winding device not illustrated on the accompanying drawings and are then further treated.

The precipitating liquid is contained in a storage tank *u* and flows from there through the pipe *s* into a regulating vessel *w* having an overflow *l*. By means of the latter the liquid level in the vessel *w* is kept at the same level. A tube *x* projects into the vessel *w* and leads to the pipe *d*. When the spinning apparatus is filled with precipitating liquid and when the discharging opening of the tube *t* is situated below the liquid level in *w* the whole spinning apparatus acts as a siphon and as long as the liquid level in the regulating vessel *w* remains constant the precipitating liquid will continuously flow through the spinning apparatus with the same speed. The latter depends on the vertical difference between the water level in the regulating vessel *w* and the discharge opening of the pipe *t*, this difference being adjusted to a determined amount. The speed at which the threads are drawn out by the winding device must be somewhat greater than the discharge velocity of the precipitating liquid from the discharge pipe *t* in order to obtain a suitable thread.

We claim:

1. In apparatus for spinning artificial silk, a spinning head, a short cylinder into which said head discharges, a hollow annular

supply member surrounding the bottom of said cylinder, closing the same and discharging thereinto, and a funnel supported by said member.

2. In apparatus for spinning artificial silk, a spinning head, a cylinder into which said head discharges, means to peripherally supply all the precipitating liquid at the bottom of said cylinder, a funnel in said cylinder through which the threads and precipitating liquid discharge, said funnel operating as a siphon to cause the liquid to fill said cylinder around the spinning head.

3. In apparatus for spinning artificial silk, a cylinder, a spinning head discharging thereinto, means to peripherally supply all the precipitating liquid at the bottom of said cylinder, a funnel supported in said cylinder with its lip above the point of supply of liquid to the cylinder, said funnel operating as a siphon to maintain said cylinder full of liquid.

4. In apparatus for spinning artificial silk, a short cylinder, a spinning head discharging thereinto, a hollow annular member on the bottom of said cylinder and discharging thereinto through an annular space, means to supply precipitating liquid to said member, a funnel supported in said member with its lip spaced from the inner wall of said cylinder, said funnel operating as a siphon to maintain the liquid in said cylinder around the head.

5. In apparatus for spinning artificial silk, a short cylinder, a spinning head discharging thereinto, a hollow annular member surrounding said cylinder and discharging at its bottom peripherally into the bottom of said cylinder, a funnel supported in said member whose lip is spaced from the inner wall of said cylinder above the entrance of liquid to the cylinder, said funnel operating as a siphon to draw the precipitating liquid through said member up into the cylinder and around said head.

In testimony that we claim the foregoing as our invention, we have signed our names.

HUBERT KEMPF.
AUGUST HARTMANN.
